COMBINATION BRUSH, SPONGE AND SCRAPER

Shephard D. Roberts, 1351 Fulton St., Brooklyn, N.Y.

Filed Mar. 29, 1965, Ser. No. 84,524

Term of patent 7 years

(Cl. D9—2)

FIG. 1

FIG. 2

FIG. 1 is a perspective view showing the side and bottom portions of a combination brush, sponge and scraper, showing my new design.

FIG. 2 is a perspective view thereof, showing the top and front portions thereof.

The side not shown is substantially the same as the side shown.

I claim:

The ornamental design for a combination brush, sponge and scraper, as shown and described.
